CLAIM

The ornamental design for a pet ramp as shown and described.

DESCRIPTION

FIG. 1 is a front view of a pet ramp according to our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof;

FIG. 8 is a perspective view of the pet ramp at another support angle;

FIG. 9 is a perspective view of the pet ramp in a lying down state;

FIG. 10 is a perspective view of the pet ramp in a folded state;

FIG. 11 is an enlarged view of area 11 indicated in FIG. 1; and,

FIG. 12 is an enlarged view of area 12 indicated in FIG. 7. The dash-dot broken lines in FIGS. 1, 7, 11 and 12 illustrate the bounds of the enlarged views and form no part of the claimed design.
